UNITED STATES PATENT OFFICE.

BYRON H. ROBB, OF NEWPORT, KENTUCKY.

GALVANIC BRUSH.

SPECIFICATION forming part of Letters Patent No. 225,723, dated March 23, 1880.

Application filed January 26, 1880.

To all whom it may concern:

Be it known that I, BYRON H. ROBB, of the city of Newport, in the county of Campbell and State of Kentucky, have invented a new and useful Improvement in Galvanic Brushes, 5 of which the following is a specification.

This invention relates to galvanic brushes, and is an improvement upon the invention for which Letters Patent No. 221,612 were granted 10 to me November 11, 1879.

The objects of these improvements are to lessen the cost of construction, to make the brush more convenient to use and more comely in appearance, and at the same time to provide 15 for the use of a more powerful battery without making the brush unhandy and cumbersome.

In the accompanying drawings, in which similar letters of reference indicate the same 20 parts in both figures, Figure 1 is a perspective view of my improved brush, and Fig. 2 is a longitudinal vertical section thereof.

A is the back or stock of the brush, which is fitted with a pin-retaining facing of the usual 25 kind now in use. Through the back of the brush is cut an oblong opening to receive a galvanic or voltaic pile. The opening in the back is covered by a similarly-shaped metal box, B, which box has an outwardly-projecting 30 flange, c, that rests upon the back A. The box is secured upon the back A by pins d and buttons e. The sides of the opening in the back and the rim of cover B are lined with a rubber ring, f, to isolate the voltaic pile from 35 the back and cover.

G is a metal spring, secured at one end to the top of the handle. It is arched up over cover B, and has its free end bent down and passed through an opening in the top of cover 40 B, where it remains in proximity to the top plate of the pile within, against which plate

it is to be pressed by the forefinger to complete the circuit when the brush is used. The opposite plate of the pile rests upon the pin-heads on the inside of the pin-retaining facing. 45

Should a stronger current be required a wire from a battery may be secured to the spring G, which is perforated to receive it, its operation in this respect being the same as the binding-post shown in my former patent, the advantage of the spring G being that by its use I am enabled to confine all the plates of the pile within the cavity of the brush, and insure a perfect closing of the circuit, whatever number of plates are used in the pile. 55

By my present improvements I am enabled to make the stock of my brush light, and at the same time obtain a battery of any desired number of plates, by increasing or lessening the depth of the light metal cover B. The pile is 60 also, by the rubber linings f, entirely isolated from the brush.

I claim—

1. The back A, having a pin-retaining facing, and recessed to receive a voltaic pile, in combination with the inverted flanged box B, adapted to fit over the recess in back A, and secured to said back by pins d and buttons e, substantially as specified. 65

2. The combination, substantially as specified, of the back A, a pin-retaining facing, the inverted box-cover B, and the binding-spring G with a voltaic pile incased within said back and cover. 70

3. The combination, substantially as specified, of the recessed back A and recessed cover B with the rubber linings f and a voltaic pile, for the purpose set forth. 75

BYRON H. ROBB.
